7 Claims. (Cl. 167—65)

This invention relates to therapeutic compositions and more particularly to compositions which are useful in the treatment of various dermatological conditions.

We have found that topical preparations comprising a combination of diphenamyl methylsulfate (4-diphenylmethylen-1,1-dimethylpiperidinium methyl sulfate) with hydrocortisone or prednisolone (1,4-pregnadiene-11 β ,17 α , 21-triol-3,20-dione) offer a long-awaited adjunct in the treatment of a variety of skin diseases. Our new compositions are useful in treating conditions such as dyshidrotic eczematous lesions caused by drug allergies. In place of the free sterol there may be used, in some cases, an ester such as a 21-acetate or soluble stable ester of phosphoric acid and the like. The composition is especially applicable in the treatment of the disease generally known as intertrigo which is aggravated by sweating and friction between opposing skin surfaces. Lesions which occur in the armpit due from sensitivity to a deodorant, for example, and the common "diaper rash" quickly disappear following local application of our therapeutic combination. Furthermore, many dermatological conditions such as lichen planus, those arising from food or drug allergies, athlete's foot, intertrigo, and the like, are accompanied by severe pruritis, or itching, with weeping of the lesion. The new compositions of this invention have demonstrated remarkable ability in overcoming pruritic and weeping manifestations. By so removing the desire to scratch and further aggravate the sores, the topical preparations hasten the cure of the disease.

The new therapeutic combinations, described in more detail below, are thus highly effective agents in combating a host of skin diseases. It is indeed surprising that the particular combination of diphenamyl methylsulfate with hydrocortisone or prednisolone enables control of conditions which are resistant to the action of either active ingredient when used alone.

The mode of action of the composition is unknown although absorption of the medicament at the site apparently occurs whereby the development of tissue reaction is counteracted. No toxic reactions arising from the composition have been observed.

There appears to be a potentiation of each of the active ingredients upon each other. Although large doses of hydrocortisone have been used internally or topically to combat certain skin diseases, the presence of diphenamyl methylsulfate permits the use of a smaller dose of the corticoid.

Our new compositions consist essentially of the active ingredients suspended or dissolved in a carrier suitable for topical application such as a hydrocarbon base of the petrolatum type, absorption bases, hydrophilic petro-latum bases, water-soluble bases containing polyethylene glycols and lotions. In certain instances a water-soluble base is preferred so as to permit proper healing of weeping lesions and overcome intertrigo. Diphenamyl methylsulfate is particularly adaptable to incorporation into water-soluble bases and water containing bases by virtue

of its stability. It is indeed surprising that of the large number of anticholinergic agents of the quaternary amine type which are in common use in medical therapy, only one, diphenamyl methylsulfate, is stable under hydrous conditions. This distinct property is not easily explained but may be due to the chemical structure of diphenamyl methylsulfate. The substance is a piperidylidene derivative while for the most part all other anticholinergics are structurally related to atropine and/or contain a dialkaminoalkyl grouping. Laboratory testing of other anticholinergic agents such as methantheline bromide, methscopolamine bromide, propantheline bromide, tricyclamol methylsulfate, and the like, have demonstrated their incompatibility with hydrous media. Thus our compositions are inherently unique in their content.

The active ingredients of our novel compositions can be incorporated into any suitable ointment or cream base to provide the topical preparations of the present invention. Representative examples of suitable bases are given in the specific examples hereinafter set forth. The nature and composition of such bases are well-known and well understood by those skilled in the preparation and employment of topical medications. While each of the active ingredients present in the compositions of the present invention is ordinarily employed in proportions of from about 0.1 percent to 2.5 percent by weight of the final composition, proportions outside this range can also be used, such as 0.1 to 4 percent diphenamyl methylsulfate and 0.1 to 4 percent steroid. For achievement of optimum results, it has been determined that the preferred proportions of the active ingredients present in the composition should be one percent of the cortical hormone and two percent of anticholinergic agent.

The compositions of the present invention can be readily prepared by conventional procedures used in the preparation of topical ointments or creams. For example, the active ingredients can be incorporated into any suitable ointment or cream base by simply admixing in a suitable agitating device, such as a mixer or blender. The novel topical medications of the present invention are illustrated by the following examples which are presented for illustrative purposes only.

EXAMPLE 1

Water soluble cream

	Parts
Prednisolone	5.0
Diphenamyl methylsulfate	20.0
Zinc stearate	60.0
Polyethylene Glycol 1500	405.0
Polyethylene Glycol 6000	120.0
Propylene glycol	350.0
Distilled H ₂ O	40.0

The steroid, prednisolone, is dissolved in the mixture of glycols by stirring and heating on a steam bath at about 75° C. Diphenamyl methylsulfate is dissolved in the distilled water. The aqueous solution is added to the stirred steroid solution. When a homogeneous mixture has been obtained, zinc stearate is dispersed throughout the mixture and the entire batch is homogenized in an ointment mill.

EXAMPLE 2

Water soluble ointment

	Parts
Diphenamyl methylsulfate	20.0
Hydrocortisone	10.0
Zinc stearate	200.0
Carbowax 1500	549.0
Distilled water	221.0

3

Hydrocortisone is dissolved in Carbowax 1500 by heating and stirring. The remaining ingredients are added in the same manner as described in Example 1.

EXAMPLE 3

Water-removable or hydrophilic preparation

	Parts
Hydrocortisone	10.00
Diphenamyl methylsulfate	40.00
Methyl Paraben	0.25
Propyl Paraben	0.15
Propyl	245.00
Steryl alcohol	245.00
White petrolatum	245.00
Propylene glycol	120.00
Polyoxyethylene lauryl alcohol	50.00
Distilled Water	290.00
	1000.00

Steryl alcohol and white petrolatum are melted together on a steam bath at about 75°. The remaining ingredients, except for the steroid, are dissolved in water. The aqueous mixture is stirred into the stearyl-alcohol-petrolatum melt. The resultant mixture is thoroughly stirred at 75° C. When proper mixing has been obtained, the mixture is allowed to cool to 50° C. Hydrocortisone is then added and the preparation is stirred and allowed to cool until it completely congeals.

EXAMPLE 4

Hydrocarbon ointment

	Parts
Prednisolone	10
Diphenamyl methylsulfate	25
Petrolatum U.S.P.	965
	1000

A slurry of the prednisolone and diphenamyl methylsulfate in about 100 parts of petrolatum is milled. The remainder of the petrolatum is then added and the batch is mixed in an ointment mixture until uniform.

EXAMPLE 5

Absorption formulation

	Parts
Cholesterol	30
Stearyl alcohol	30
White wax	80
White petrolatum	830
Diphenamyl methylsulfate	20
Hydrocortisone	10
	50

Cholesterol is added to a warm melt of the stearyl alcohol, wax, and petrolatum. The mixture is stirred until the cholesterol completely dissolves. Hydrocortisone is then mixed in by stirring. Diphenamyl methylsulfate is added and the mixture is thoroughly stirred and cooled until it congeals.

4

EXAMPLE 6

Lotion preparation

	Parts
5 Diphenamyl methylsulfate	30
Prednisolone	5
Methyl Paraben	0.25
Propyl Paraben	0.15
Stearyl alcohol	245
10 Propylene glycol	50
Polyoxyethylene lauryl alcohol	10
Distilled water, q.s. to a total of 1000 parts.	

This formulation is prepared in the same manner as the hydrophilic preparation of Example 3 except that the petrolatum is omitted.

Having disclosed our invention, what we claim to be new and wish to secure by Letters Patent is:

1. A therapeutic composition of matter comprising a steroid of the group consisting of hydrocortisone and prednisolone in combination with diphenamyl methylsulfate and a carrier.

2. A therapeutic composition of matter comprising from about 0.1 percent to about 4.0 percent of a steroid defined in claim 1, from about 0.1 percent to about 4.0 percent diphenamyl methylsulfate, the remainder of the composition comprising a viscous supporting carrier.

3. A therapeutic composition of matter comprising from about 0.1 percent to about 2.5 percent of a steroid defined in claim 1, from about 0.1 percent to about 2.5 percent of diphenamyl methylsulfate, the remainder of the composition comprising a viscous supporting carrier.

4. A therapeutic composition of matter according to claim 2 in which the steroid is hydrocortisone.

5. A therapeutic composition of matter according to claim 2 in which the steroid is prednisolone.

6. A therapeutic composition of matter comprising essentially the following:

	Percent by weight
40 Prednisolone	0.1 to 2.5
Diphenamyl methylsulfate	0.1 to 2.5

in an aqueous glycol vehicle.

7. A therapeutic composition of matter comprising essentially the following:

	Percent by weight
Hydrocortisone	0.1 to 2.5
Diphenamyl methylsulfate	0.1 to 2.5

in an aqueous glycol vehicle.
